UNITED STATES PATENT OFFICE

2,420,044

GUN SWAB OR CLEANER

John A. Jowett, Scottsville, N. Y.

Application April 28, 1944, Serial No. 533,211

3 Claims. (Cl. 15—104.165)

1

My invention relates to gun swabs or cleaners. An object of my invention is to provide an improved gun swab or cleaner which is economical to manufacture and effective in use.

Another object of my invention is to provide a gun swab which is of uniform diameter and wound helically around a supporting rod so that the swab, during cleaning of the gun, will more or less follow the rifling of the gun barrel.

My invention further contemplates the provision of a gun swab or cleaner wherein a strip of textile material is intertwined with wire and cut so as to form a pile bristling radially with respect to the wire, the strip being wound around a supporting rod with the ends of the wire so arranged that they are covered in such manner as to protect the gun barrel against abrasion or scoring during cleaning.

Other objects and advantages of my invention will be set forth in the claims and will be apparent from the following description, when taken in connection with the accompanying drawings, in which:

Fig. 1 is a view showing the gun swab of my invention in unwound condition with the ends inserted in openings in the supporting rod;

Fig. 2 is a view similar to Fig. 1 with the supporting rod partly wound with the cleaning material;

Fig. 3 is an enlarged view of Fig. 1 to better illustrate the manner in which the ends of the cleaning strip are covered;

Fig. 4 is a view showing the completed gun swab.

Heretofore most gun swabs merely have comprised a supporting rod with a slot extending therethrough through which a rag or other strip of textile material was threaded. In using such a swab the end thereof is entered into the barrel of the gun and twisted as it is inserted. This more or less winds the rag or cleaning element about the rod, but usually not in a uniform manner. The cleaning element or strip tends to bunch eccentric with respect to the supporting rod. Effective cleaning of the gun is difficult and the swab does not effectively reach the crevices formed by the rifling. Many other types of gun swabs have appeared on the market, such as brushes made of brass wire or other stiff materials. For the most part these either have been expensive or have been little or no more effective than the conventional gun swab mentioned above.

The gun swab or cleaner of my invention comprises a rod or support 11 of any suitable material. I have found a tube of plastic material

2

to be extremely satisfactory as it is available in varying diameters and may be conveniently cut to the desired lengths. The diameter of the supporting tube will, of course, vary with the calibre of the gun to be cleaned.

At a point removed from the end of the rod or tube an opening or slot is cut which preferably does not extend through both walls of the tube. The ends of the tube are left open as indicated at 13 and 14. If desired a solid rod may be used instead of a tube. The slot 12 may then be cut in the rod and one or both ends of the rod bored to provide openings equivalent to the open ends of the tube.

15 While other suitable materials might be wound about the tube in the manner indicated in the drawings to provide the cleaning element, I have found a cleaning element made up in the manner described herein much more effective for the purpose. The cleaning element of the swab is

20 preferably made by twisting two wires 16 and 17 in intertwining relationship with a strip, strand or length 18 of textile, cord or other suitable material. I have found a common light cord or string suitable for the purpose. After the cord and wires have been wound or twisted together the strip or length of material thus formed and suitable knives are rotated and fed with respect to each other so as to cut the textile ma-

25 terial or cord and not damage or cut the wires. The cut cord bristles radially with respect to the wires to form a pile held in position by the twisted wires. The method of manufacture need not be described in greater detail since it 30 is similar to the methods conventionally employed in the manufacture of pipe cleaners and is well known.

This strip or length of pile thus formed, generally indicated by the numeral 18, after being cut 40 to the length desired has one end thereof inserted in the slot 12 in the manner illustrated at 21 in Figs. 1 and 3. The end of the strip of pile material is held in position by applying adhesive to the end of the strip, as indicated at 22, in Fig. 3.

45 The opposite end of the strip is entered into the open end of the tube, as indicated in the drawings, and adhesively secured in the open end of the tube as shown at 23. The intermediate portions of the strip of pile material are wound upon 50 the rod in the manner illustrated in Fig. 2 in the form of a helix, the turns of the helix being adhesively secured to the rod as the strip is wound. While I have shown the end of the strip in Fig. 2 inserted in the open end of the tube prior to the completion of winding, it is obvious that the

winding on the tube may be completed and then the free end of the strip tucked in the open end of the tube.

When completed the swab or gun cleaner appears as shown in Fig. 4. It will be noted that the cleaning portion of the swab is of uniform diameter so that it may be made up to properly fit any calibre of gun or rifle desired. The overall diameter of the cleaning element is made slightly larger than the diameter of the bore of the gun so that the pile material may be somewhat crushed as it enters the gun with the ends of the pile in intimate contact with the bore.

Due to the helical winding and the fact that the swab is of uniform diameter a slight twisting of the swab as it is entered is all that is necessary to cause the swab to more or less follow the rifling of the gun bore to thereby enable the bristles or pile to enter the crevices formed by the rifling to secure effective cleaning. Of major importance is the fact that the ends of the wire are covered or confined within the rod so that the sharp ends can not score or abrade the gun bore.

As shown in Figs. 1 and 2 the opposite end of the tube is formed with a slot 26 so that if desired a similar cleaning element may be secured in position on the other end of the tube. Thus one end of the swab may be used for cleaning the gun barrel while the other end may be used for applying oil. The swabs are inexpensive to manufacture and after use several times may be thrown away or cleaned. If desired, cleaning elements more or less as appearing in Fig. 4 may be made up for attachment to a permanent gun swab rod. In such case all that is necessary is to renew the cleaning end or ends of the swab.

While I have shown and described the preferred form of my invention, it will be appreciated that various changes and modifications may be made therein, particularly in the form and relation of parts, without departing from the spirit of my invention as set forth in the appended claims.

I claim:

1. A gun swab comprising a tubular rod having an open end and an opening between its ends, a strip of non-abrasive cleaning material having a wire intertwined therewith, said strip having one of its ends inserted in said opening extended into said rod and enclosed by the walls thereof, its intermediate portions wound helically on said rod and its other end inserted in the open end of said rod and enclosed by the walls thereof.
2. A gun swab comprising a tubular rod having an opening between its ends and an open end, a strip of cleaning material intertwined with a pair of wires and cut so as to form a pile bristling radially of the wire, said strip having one of its ends inserted in said opening, its intermediate portions wound helically on said rod and its other end inserted in the open end of said rod.
3. A gun swab comprising a tubular rod having an opening between its ends and an open end, a strip of cleaning material intertwined with a pair of wires and cut so as to form a pile bristling radially of the wire, said strip having one of its ends inserted in said opening and adhesively secured to the internal sidewalls of the rod, its intermediate portions wound helically on said rod and adhesively secured to the external sidewalls thereof and its other end inserted in the open end of said rod and adhesively secured to the internal sidewalls thereof.

JOHN A. JOWETT.
